UNITED STATES PATENT OFFICE.

ERNEST P. CLARK, OF NEW YORK, N. Y., ASSIGNOR TO THE CLARK ELECTRIC COMPANY, OF SAME PLACE.

SAFETY DEVICE FOR DYNAMOS.

SPECIFICATION forming part of Letters Patent No. 426,108, dated April 22, 1890.

Application filed December 30, 1889. Serial No. 335,298. (No model.)

To all whom it may concern:

Be it known that I, ERNEST P. CLARK, a citizen of the United States, residing in New York city, in the county of New York and 5 State of New York, have invented certain new and useful Improvements in Safety Devices for Dynamo-Electric Machines, of which the following is a specification.

In the operation of shunt-wound dynamos 10 designed for a constant current with varying electro-motive force for the purpose of supplying arc lights in series or other similar purpose a difficulty sometimes arises from the characteristic action of such a machine, 15 which tends to increase the electro-motive force of the dynamo whenever from any cause the resistance of the circuit is increased. With such machines, if the main circuit is broken by accident or otherwise, the electro- 20 motive force of the dynamo rises at once and in a few seconds becomes much greater than the normal working electro-motive force. This action renders the broken line very dangerous to persons or animals coming in contact with 25 it. At the same time the increased electro-motive force may become injurious to the insulation of the dynamo-coils. If, now, the broken line should be joined again, it would practically have the effect of placing the dynamo on short circuit, as the dynamo is generating 30 a very high electro-motive force and all the lamps or other devices included in the circuit are in their condition of lowest resistance. The result of closing the line (by 35 accident or otherwise) at such a time is to cause an enormous rush of current and great strains on the armature and shaft of the dynamo, which may even be great enough to wreck the machine. If an automatic regulator 40 is used in connection with such a dynamo, the results are really worse, for the reason that the regulator of such a machine operates to increase the electro-motive force when the resistance rises, and thus maintains 45 a constant current with varying electro-motive force. If the main circuit of a dynamo provided with such a regulator is broken, the result is an immediate rise of electro-motive force to the utmost limit that the machine is 50 capable of producing.

The object of this invention is to provide a

means for throwing the dynamo out of action in the event of a rupture of the main circuit, and to accomplish this result without danger to the dynamo and quickly enough to prevent any considerable rise in its electro-motive force. 55

The invention is illustrated in the accompanying drawings, in which—

Figure 1 represents a general diagram of 60 the circuits and apparatus used; and Fig. 2 represents a detail of a portion of the apparatus.

A represents a dynamo-electric machine whose main circuit is B and whose field-magnets are in the shunt-circuit C. The shunt-circuit also includes a switch-arm c and a regulator C'. The switch-arm is fitted with a contact-shoe c', which normally bears upon a contact-piece c². A spring c³ is attached to 70 the arm c in such a manner that it tends to draw it over against the stop-pin c⁴ to break the shunt-circuit. In making this movement the shoe c' is brought momentarily into connection with a second contact-piece c⁵. This 75 throws a circuit D containing a resistance d into the shunt-circuit for a purpose which will be explained later. There is also connected with the switch-arm the piston-rod of an air-cushion c⁶. This is arranged so that 80 the first movement of the arm to break the circuit will be rapid; but immediately the motion is retarded while the shoe is passing over the second contact. The switch-arm is maintained in its normal position by a latch 85 e, which is pivoted at c' and carries on one end a hook which engages with the arm and on the other end a soft-iron bar constituting the armature of a magnet E, included in the main circuit of the dynamo. So long as the 90 magnet is sufficiently energized the armature is held up and locks the switch-arm; but when the magnet becomes de-energized or abnormally weakened the armature drops of its own weight, or by reason of a spring e², 95 and releases the switch-arm.

The core of magnet E is made hollow and a push-rod e² placed therein, by which the armature may be driven away from the pole of the magnet. 100

The operation of the device is as follows: As long as the main circuit is intact and the

current flowing therein is nearly or quite normal the latch and switch remain as shown; but if now the main circuit is broken, or for any reason the main current is very much decreased, the latch e is no longer held in position by the magnet, but drops, releasing the arm c , which is drawn by the spiral spring toward the stop-pin, thus breaking the field-magnet circuit and throwing the dynamo out of action. If this were all the action of the device there would be a serious arc formed when the arm c left the contact c^2 , and the extra current produced by suddenly breaking the field-magnet circuit would be liable to rupture the insulation of the field-coils. To avoid this action the second contact c^5 is introduced in the path traversed by the arm c , which second contact is connected in the shunt through the coil of high resistance, as hereinbefore described. The extra current is therefore discharged through this coil. The movement of the arm from contact c^2 to contact c^5 being rapid, the air in the cushion becomes compressed and retards the movement of the arm. This retardation is aided by the weakened condition of the spring, and the arm therefore moves slowly over contact c^5 while the air is escaping from the cushion. The continued movement of the arm finally breaks the field-magnet circuit entirely. The machine then ceases to generate current, and no harm can come from handling the conductors in any part of the circuit. In order to put the machine into action again the arm c must be moved to its original position by hand and held there until the main current being once more established the electro-magnet E will hold its armature and thus lock the arm in position. When it is desired to stop the action of the dynamo, it is only necessary to force the armature-latch e away from the electro-magnet E , the arm c performing its functions, as before described. This may be accomplished by the rod e^2 . If the dynamo is stopped, the arm acts as before, and must necessarily be used whenever the dynamo is set at work, thus insuring that it shall always be in working order and ready to operate in case of an emergency.

Having thus described my invention, I claim—

1. The combination, with a shunt-wound constant-current dynamo, of a make-and-break switch located in its field-magnet cir-

cuit, and in its main circuit an electro-magnetic device for holding said switch in its closed position, and means for opening the switch when it has been released by said electro-magnet, substantially as described.

2. An automatic safety device for dynamos, consisting of a switch-arm included in the field-magnet circuit and acted upon by a spring or its equivalent, in combination with a magnet in the main circuit of the dynamo, said magnet acting when energized to maintain the switch-arm in its closed position, and when de-energized to release the switch-arm and allow the spring to act and break the field-magnet circuit.

3. An automatic safety device for shunt-wound dynamos, consisting of a switch included in the field-magnet circuit, a catch for holding the switch in its closed condition, a spring acting upon the switch tending to break the field-magnet circuit, and a second contact-piece in the path of the switch-arm, said second contact-piece being connected with the main or first contact through a resistance, as and for the purpose set forth.

4. An automatic safety device for shunt-wound dynamos, consisting of a switch included in the field-magnet circuit, a catch for holding the switch in its closed condition, a spring acting upon the switch tending to break the field-magnet circuit, a second contact-piece in the path of the switch-arm, said contact-piece being connected to the main or first contact through a resistance, and a retarding device arranged to check the motion of the switch-arm while it is passing over the second contact, substantially as and for the purpose set forth.

5. An automatic safety device for shunt-wound dynamos, consisting of a switch-arm in the field-magnet circuit and a spring tending to move the switch-arm to break the circuit, a latch for holding the switch-arm closed, and a magnet in the main circuit for holding the latch in engagement with the switch, as described.

In witness whereof I have hereunto signed my name in the presence of two subscribing witnesses.

ERNEST P. CLARK.
